DESIGN FOR A REED FOR A WIND INSTRUMENT

Edward Schwartz, New York, N. Y., assignor to
Arnold Brilhart, Great Neck, N. Y.

Application January 15, 1940, Serial No. 89,465

Term of patent 14 years

To all whom it may concern:

Be it known that I, Edward Schwartz, a citizen of the United States and a resident of the city of New York, county of New York, State of New York, have invented a new, original, and ornamental Design for a Reed for a Wind Instrument, of which the following is a specification, reference being had to the accompanying drawing, forming part thereof.

Fig. 1 is a perspective view of a reed for a wind instrument, showing my new design; and
Fig. 2 is a side elevational view thereof.

I claim:

The ornamental design for a reed for a wind instrument, substantially as shown.

EDWARD SCHWARTZ.
